(57) **CLAIM**

The ornamental design for a cap for pen, as shown and described.

DESCRIPTION

FIG. 1 is a perspective view of a cap for pen showing my new design in accordance with a first embodiment;

FIG. 2 is a front view thereof;

FIG. 3 is a rear view thereof;

FIG. 4 is a left side view thereof;

FIG. 5 is a right side view thereof;

FIG. 6 is a top view thereof, with the bottom view being a mirror image thereof;

FIG. 7 is a sectional view along a line 7-7 in FIG. 2;

FIG. 8 is a perspective view of a cap for pen showing my new design in accordance with a second embodiment;

FIG. 9 is a front view thereof;

FIG. 10 is a rear view thereof;

FIG. 11 is a left side view thereof;

FIG. 12 is a right side view thereof;

FIG. 13 is a top view thereof, with the bottom view being a mirror image thereof;

FIG. 14 is a sectional view along a line 14-14 in FIG. 9;

FIG. 15 is a perspective view of a cap for pen showing my new design in accordance with a third embodiment;

FIG. 16 is a front view thereof;

FIG. 17 is a rear view thereof;

FIG. 18 is a left side view thereof;

FIG. 19 is a right side view thereof;

FIG. 20 is a top view thereof, with the bottom view being a mirror image thereof;

FIG. 21 is a sectional view along a line 21-21 in FIG. 16;

FIG. 22 is a perspective view of a cap for pen showing my new design in accordance with a fourth embodiment;

FIG. 23 is a front view thereof;

FIG. 24 is a rear view thereof;

FIG. 25 is a left side view thereof;

FIG. 26 is a right side view thereof;

FIG. 27 is a top view thereof, with the bottom view being a mirror image thereof; and,

FIG. 28 is a sectional view along a line 28-28 in FIG. 23.
